ABSTRACT: A panel joint construction having a first panel with a first rearwardly directed flange portion and a second panel having a second rearwardly directed flange portion terminating in an end sector disposed rearwardly of the first panel. A panel clip receiver element secured to one panel and a panel clip secured to the other with the panel clip engaged within the panel clip receiver. The panel clip receiver element having a base portion secured to one panel and two forwardly extending receiver sidewalls each terminating in inwardly rearwardly directed locking flanges. The panel clip secured to the other panel having an anchoring wall and a projecting tongue extending into the panel clip receiver between the locking flanges. Adjustable means permitting variable locking penetration of the projecting tongue into the receiver. The forwardly extending receiver sidewalls may be inclined transversely inwardly toward each other at an angle of about 2° to 15° with respect to a plane perpendicular to the receiver base. The included angle between the locking flanges and the adjacent receiver sidewall being about 25° to 45°.

PANEL JOINT CONSTRUCTION

BACKGROUND OF THE INVENTION

1. Field of the Invention

This invention relates to a panel clip assembly for adjustably joining adjacent panels and more specifically this invention relates to a uniquely configurated panel clip element adapted to be presecured to one panel and received within a panel clip receiver element which is adapted to be presecured to the other panel in forming a joint between adjacent panels.

2. Description of the Prior Art

Numerous means of joining panel elements to establish exterior wall structures as well as interior partition walls have been known. Various forms of hardware adapted for effecting joinder between overlapping or abutting panel edges have been provided.

One difficulty encountered with respect to a number of panel-joining elements is the lack of adjustability provided within the anchoring hardware. Adjustment of the locked relative position of one panel with respect to the other, therefore, cannot be readily effected. Also, numerous panel-joining components require extensive effort in the field in order to first secure the joint-forming hardware to the panel edges. Also, frequently extensive joining effort is required in the field after the initial affixation has been completed in order to effect final panel joinder.

In such installations economic considerations make it important to limit the amount of required field labor to an absolute minimum, and also to carefully control the cost of materials.

Another problem is the aesthetically unpleasing appearance of panel joints established by many known systems.

An additional inconvenience frequently encountered is the need to employ different hardware for header and sill attachment than that employed in the vertical joints between adjacent panels.

SUMMARY OF THE INVENTION

The joint-forming elements of the present invention solves the previously enumerated problems in an economical and effective fashion.

This invention provides complementary relatively adjustable interengaging panel clip and panel clip receiver elements which may be conveniently and economically made in a conventional manner, as by extrusion.

The panel clip element has an anchoring wall, a serrated projecting tongue and a transitional wall connecting the anchoring wall with the serrated projecting tongue. The projecting tongue has a rearwardly disposed end provided with outwardly diverging pilot surfaces adapted to engage the panel clip receiver and guide the tongue in the receiver opening. Each serration has a first serration-defining face oriented generally perpendicular to the longitudinal axis of the tongue and a second serration-defining face oriented generally parallel to the pilot surface portion disposed on the same side of the longitudinal tongue axis.

A generally channel-shaped panel clip receiver has a base portion and a pair of spaced sidewalls extending forwardly from opposite sides of the base portion and a pair of angularly rearwardly disposed locking flanges connected to the forward ends of said forwardly directed sidewalls and terminating in free ends spaced from each other and defining the receiver opening. The included angle between the locking flanges and said forwardly directed sidewalls is preferably about 25° to 45°.

It is an object of this invention to provide a panel joint construction wherein adjacent panel members may be adjustably secured to each other by means of panel clip components having two parts which are adapted to be presecured to the panels to be joined.

It is a further object of this invention to provide a panel clip assembly having component parts which are adapted to be

economically manufactured and installed and permit adjustable interengagement between the respective elements to permit panel securement in a predetermined position relative to adjacent structural elements.

5 It is another object of this invention to provide a panel clip assembly wherein the same components may be employed to secure joints between adjacent panels as well as header or sill joints.

10 It is yet another object of this invention to provide such a panel clip assembly which will provide an aesthetically pleasing joint and reduce the amount of field labor required and yet provide readily effected locking engagement.

15 These and other objects of this invention will be more fully understood from the following description of the invention, on reference to the illustrations appended hereto.

BRIEF DESCRIPTION OF THE DRAWINGS

FIG. 1 is an elevational view showing a portion of a wall 20 constructed in accordance with this invention.

FIG. 2 is a fragmentary sectional view of the wall construction of FIG. 1 taken through 2—2.

FIG. 3 is a fragmentary sectional view of the wall construction of FIG. 1 taken through 3—3.

25 FIG. 4 is a cross-sectional view of a form of panel clip receiver of this invention.

FIG. 5 is a cross-sectional view of a form of panel clip of this invention.

30 FIG. 6 shows a partial sectional detail of the locking engagement provided by this invention.

DESCRIPTION OF THE PREFERRED EMBODIMENTS

Referring now more specifically to the drawings with 35 reference to FIGS. 1 through 3, it is seen that a ribbed wall construction 2 is formed from a number of plastic panels 4 which are joined at adjacent ends to provide vertical joints 6.

A detail of a vertical joint 6 is shown in FIG. 3. (Solely for simplicity of description, as used herein, the terms "forward" and 40 "forwardly" and words of similar import shall refer to the direction toward which the exposed surface of wall construction 2, as shown in FIG. 1, faces and the terms "rear" and "rearwardly" and words of similar import shall refer to the direction toward which the concealed or unexposed surface of wall construction 4 faces.) As is there illustrated, a first panel element 10 has a first generally rearwardly directed flange portion 12. An adjacent second panel 14 has a second generally rearwardly directed flange portion 16 which terminates in an end sector 18 disposed rearwardly of the first panel 10. First panel 10 has a forwardly exposed surface 20 and a rearwardly exposed surface 22. Second panel 14 has a forwardly exposed surface 24 and a rearwardly exposed surface 26. For convenience of reference these surfaces 20, 22, 24 and 26 will be considered as extending the full extent of the respective panels 10, 14.

45 A panel clip 30 as shown is secured to first flange 12 by means of a rivet 32. A panel clip receiver 40 as shown is secured to end sector 18 of first panel element 10 by means of a rivet 42. This feature of the invention permits a reduction in the amount of effort required in the field by facilitating factory presecurement of the panel clip 30 and panel clip receiver 40 to the respective panels 10, 14. This may be accomplished by the preferred mechanical fastening means, such as rivet 32, 42, or by other suitable means including adhesive materials.

50 Referring now more specifically to the detailed configuration of the panel clip 30 and panel clip receiver 40, reference is made to FIGS. 4 and 5. The panel clip receiver 40 has a base portion 44 and forwardly extending receiver sidewalls 46 which terminate in rearwardly and transversely inwardly directed locking flanges 48. The receiver sidewalls 46 are preferably inclined slightly inwardly toward each other with respect to planes perpendicular to base element 44 at the base of the sidewalls 46. This inclination is represented by the angle 55 A in FIG. 4 and is preferably about 2° to 15°. In order to pro-

75 A in FIG. 4 and is preferably about 2° to 15°. In order to pro-

vide for resilient deflection of the locking flanges 48 during panel clip engagement, the receiver 40 is preferably made of thinner material than panel clip 30.

The locking flanges 48 preferably taper toward their free ends 50 which are disposed in spaced relationship with respect to each other and define receiver opening 52 therebetween. The included angle B between a receiver sidewall 46 and the adjacent connected locking flange 48 is preferably about 25° to 45° in order to provide for ease of insertion of the panel clip 30 and effective locking engagement between the clip 30 and receiver 40.

The panel clip receiver 40 is preferably provided with a substantially uniform cross-sectional configuration throughout its longitudinal extent with or without preformed fastener-receiving openings where required or desired. This may be conveniently accomplished by extrusion, for example. The clip may be made from a suitable metal, such as aluminum, plastic or other material possessing sufficient strength and resiliency.

The panel clip 30 has an anchoring wall 60, a projecting tongue 62 and an interposed connecting transitional wall 64. The projecting tongue 62 terminates in a free end 66 having pilot or guide surfaces 68 on opposite sides thereof. A plurality of integrally formed serrations 70 are formed on the transverse sidewalls of the projecting tongue 62 which is preferably substantially rigid. In the form shown the serrations of one wall are axially aligned with and coextensive with the serrations of the other wall to provide symmetry about a plane through the longitudinal tongue axis. Each serration defines a recess 72 between a forwardly exposed face 74 which is disposed substantially perpendicular to the longitudinal axis of projecting tongue 62 and an angularly forwardly directed face 76 originating at the transverse inner portion of the forwardly exposed face 74. In the form shown the maximum transverse diameter of the tongue 62 is greater than the thickness of either anchoring wall 60 or transitional wall 64. The panel clip element may be conveniently made in such fashion that it has a substantially uniform cross-sectional configuration throughout its longitudinal extent with or without preformed fastener-receiving openings.

The receiver opening 52 defined between free ends 50 of panel clip receiver 40 is not as wide as the maximum transverse diameter of projecting tongue 62. In effecting the joint shown in FIG. 3 the panels 10, 14 are first aligned so that projecting tongue 62 of panel clip 30 is aligned with the receiver opening 52 in panel clip receiver 40. Relative closing movement between the two panels is then effected in order to cause pilot surface 68 of panel clip 30 to engage locking flanges 48 of panel clip receiver 40, and thereby center projecting tongue 62 with respect to the receiver opening 52. Continued relative closing movement causes the tongue 62 through contact between the pilot surfaces 68 and locking flanges 48 to resiliently angularly rearwardly displace locking flanges 48 and thereby permit entry of projecting tongue 62 into panel clip receiver 40. As several serration 70 are preferably provided, the projecting tongue 62 may be locked in one of several positions with respect to the panel clip receiver 40 to establish the desired position of the panels 10, 14.

As is shown in FIG. 6, angularly disposed faces 76 of serrations 70 will be oriented generally parallel to locking flanges 48, and will provide for relative sliding movement between faces 76 and locking flanges 48 and rearward resilient deformation of locking flanges 48 as projecting tongue 62 is moved into receiver 40. Forwardly disposed faces 74 will provide locking engagement with the locking flange 48 and thereby resist relative separation of the panel clip parts 30, 40. It will also be seen that the orientation of the faces 74, 76 coupled with the tapered configuration of the locking flanges 48 causes the latter to substantially completely fill the serration recess 72 and have its forwardly exposed faces 78 in surface to surface contact with faces 76 when locking is effected.

Referring once again to FIG. 3, it is seen that the anchoring wall 60 of panel clip 30 is secured in surface to surface engagement with rearwardly exposed surface 22 of first panel

10. The base portion 44 of panel clip receiver 40 is secured in surface to surface engagement with outer surface 24 of first panel element 10. With this sort of securement to the respective panels and locking interengagement between panel clip 30 and panel clip receiver 40, the first generally rearwardly directed flange 12 of panel 10 cooperates with second panel flange 16 to define a forwardly open rearwardly converging recess 80. As shown, the rearward end of flange 12 contacts panel 14 and is therefore rearwardly substantially coextensive with flange 16. This results in not only an aesthetically pleasing break in the outer surface appearance of the wall construction 2 but in addition also permits solely the exterior surfaces 20, 24 which are generally the decorative panel surfaces to be forwardly exposed. Thus, unsightly hardware and unfinished panel surfaces are concealed from view.

Referring now more specifically to the fragmentary elevational section of FIG. 2, it is seen the sill joint is effecting between a starter strip 90 which is similar in configuration to flange 16 and end sector 18 shown in FIG. 3. A panel clip receiver 92 is secured to starter strip 90 by means of a suitable fastener. A panel end 94 has a panel clip 96 secured to it by a suitable fastener. The panel clip 96 and panel clip receiver 92 are of the same configuration described above and are interengaged in the same fashion.

The header portion in the form illustrated provides a panel flange 100 which is received within a header channel 102. In effecting this joint the flange 100 is first inserted into header channel 102. The panel end 94 is then rotated inwardly to establish engagement between panel clip 96 and panel clip receiver 92. As a result of the serrated projecting tongue configuration of panel clip 92, the sill portion of the panel may be anchored in the precise position desired by terminating relative closing movement between the panel end 94 and starter strip 90.

The relative length of the panel clip 30 and panel clip receiver 40 may be generally equal. In order to provide maximum adjustable interengagement, it is preferred to provide a receiver 40 which is longer than the panel clip 30 to fully ensure complete engagement of the tongue serrations. This is the more economical approach as the receiver is preferably made of thinner gauge material. If desired, the clip elements 30, 40 may be substantially coextensive with the length of the panel ends to be joined, but it is generally more economical and preferred to provide several independent panel clip assemblies of total combined length substantially less than the length of the panel edges to be joined. While, if desired, the serrations and/or locking flanges may be made longitudinally discontinuous, maximum locking interengagement is obtained when they are both substantially continuous.

The panel clip 30 and panel clip receiver 40 are effectively restrained against relative separating movement as by withdraw of the projecting tongue 62 from the receiver 40. It will be appreciated, however, that in the preferred form each element 30, 40 is of substantially uniform cross-sectional configuration throughout its longitudinal extent. Panel clip 30 and panel clip receiver 40 are therefore so configurated as to permit relative free-sliding movement between the same responsive to movement of the panel to which it is secured. This feature is of great significance as it permits such sliding movement at the joint responsive to panel expansion and contraction under the influence of changes in thermal conditions. The resistance to such relative sliding movement consists solely of frictional resistance provided by contacting surfaces of the clip 30 and receiver 40. As the extent of contact is kept to a relative minimum, without impairing the structural integrity of the joints, this frictional resistance will be relatively low. Such expansion and contraction provides a desirable thermal break within the joint structure while maintaining effective joint integrity and an aesthetically pleasing joint assembly which conceals the joint hardware from exterior view and permits exposure of only the decorative exterior surfaces of the panels.

While for purposes of illustration specific forms of ribbed plastic panel structures have been shown, it will be ap-

preciated that the benefits of this invention may be obtained with a broad range of panel materials and structures. Also, for purposes of simplicity of illustration the panel clip elements have been shown as being secured in surface to surface contact at specific panel locations, but it will be appreciated that these locations may be varied while retaining the benefits of this invention. The panel to panel joints are provided without securing of the panel clip elements to studs or underlying building framework. It will, therefore, be appreciated that this invention provides an economical and effective means of establishing an adjustable yet firm locking joint between adjacent panel elements as well as between a panel end and a header or sill. MULTiple hardware is therefore eliminated. It will also be appreciated that in addition to providing an effective joint structure, the joint assembly of this invention provides a concealed fastening system that permits movement responsive to thermal expansion and contraction. It is adapted to be readily employed with a wide range of panel materials to be simply joined in the field without substantial time consumption or the need for special equipment or specially trained workers. The components may be economically manufactured and presecured to the panel elements at the factory.

Whereas particular embodiments of the invention have been described above for purposes of illustration, it will be evident to those skilled in the art that numerous variations of the details may be made without departing from the invention as defined in the appended claims.

1. A panel joint construction comprising,
a first panel having a first generally rearwardly directed flange portion, 30
a second panel having a second generally rearwardly directed flange portion terminating in an end sector disposed rearwardly of said first panel, 35
a panel clip receiver element secured to said end sector of said second panel having a base portion and two forwardly extending receiver sidewalls each terminating in transversely inwardly rearwardly directed locking flanges, 40
a panel clip secured to said first panel having an anchoring wall and a projecting tongue extending into said panel clip receiver between said locking flanges, 45
said panel clip having serrations on opposed transverse walls thereof, and
each said locking flange engaged within a recess in said serrations to resist relative separation of said panel clip from said panel clip receiver.

2. The panel joint construction of claim 1, including
said panel clip having said anchor portion secured to said first rearwardly directed flange portion of said first panel, 50
said panel clip having a transition portion interposed between said anchor portion and said projecting tongue, and
said forwardly extending receiver sidewalls inclined transversely inwardly toward each other as they extend outwardly.

3. The panel joint construction of claim 2, including
each said first and second panels having a forwardly exposed face and a rearwardly exposed face, 60
said panel clip receiver secured to the outwardly exposed face of said end sector of said second panel, and
said panel clip secured to the rearwardly exposed face of said first rearwardly directed flange.

4. The panel joint construction of claim 3, including
at least one of said serrations of said panel-clip-projecting tongue defined by a forwardly exposed face disposed substantially perpendicular to the longitudinal axis of said tongue and an angularly forwardly directed face originating at the transverse inner portion of said forwardly exposed face, and
said angularly forwardly directed face oriented generally parallel to the adjacent locking flanges of said panel clip receiver.

5. The panel joint construction of claim 3, including

mechanical fastening means securing said panel clip to said first panel and said panel clip receiver to said second panel,

a plurality of said serrations provided on each said opposed transverse wall of said panel clip,

said serrations of one said transverse wall being axially aligned with said serrations of said other transverse wall, and

said forwardly extending receiver sidewalls each disposed at an angle of about 2° to 15° with respect to planes disposed perpendicular to said panel clip receiver base at the origin of said receiver sidewalls.

6. The panel joint construction of claim 5, including
said panel clip and panel clip receiver are each composed of metal, and are of substantially uniform cross section throughout their longitudinal extent, the free end of said projecting tongue of said panel clip having forwardly diverging pilot surfaces adapted to cooperate with said receiver locking flanges in guiding said projecting tongue into said panel clip receiver, and the included angle between each said locking flange and each said receiver sidewall being about 25° to 45°.

7. The panel joint construction of claim 3, including
said first generally rearwardly directed flange portion of said first panel and said second generally rearwardly directed flange portion of said second panel disposed with their outer surfaces generally facing each other, said first and second rearwardly directed flange portions cooperating to define a forwardly open, rearwardly converging opening therebetween, each of said locking flanges of said panel clip receiver being tapered toward their free ends and terminating in an end having a thickness which substantially completely fills the serration of said tongue within which it is engaged, and the maximum transverse width of said tongue across said serrations being greater than the width of the receiver opening defined by said free ends of said locking flanges.

8. A panel clip assembly comprising,
a generally channel-shaped panel clip receiver having a base portion, a pair of spaced forwardly directed sidewalls extending from opposed sides of said base portion and a pair of angularly rearwardly disposed locking flanges connected to the outer ends of said forwardly directed sidewalls and terminating in free ends spaced from each other and defining a receiver opening, 50
a panel clip having an anchoring wall, a projecting tongue having integrally formed serrations and a transitional wall connecting said anchoring wall and said serrated projecting tongue, 55
said projecting tongue having a rearwardly disposed free end having forwardly diverging pilot surfaces adapted to enter said receiver opening by engaging and resiliently spreading said receiver locking flanges,

said serration disposed on opposed sidewalls of said projecting tongue, and
at least a major number of said serrations having a recess defined by a first serration defining face oriented generally perpendicular to the longitudinal axis of said projecting tongue and a second serration defining face oriented generally parallel to the portion of said pilot surface on the same side of said longitudinal axis.

9. The panel clip assembly of claim 8, including
said projecting tongue is substantially rigid, 60
said panel clip and panel clip receiver are composed of aluminum and have a substantially uniform cross section throughout their longitudinal extent, 65
said outwardly directed sidewalls are each inclined inwardly toward each other at an angle of about 2° to 15° with respect to planes perpendicular to said base portion, and the included angle between each said locking flange and the adjacent forwardly directed sidewall is about 25° to 45°.

10. The panel clip assembly of claim 9, comprising

said projecting tongue adapted to have its free end extending into said panel clip receiver with said free ends of said receiver-locking flanges engaged within recesses of serrations on opposed walls of said tongue and said second serration-defining surface in surface to surface contact with the generally forwardly facing surface of said locking flanges,
said locking flanges tapered toward said free ends,

said anchor portion of said panel clip and said projecting tongue of said panel clip disposed in generally parallel spaced relationship with respect to each other, and said panel clip transition wall having one section disposed generally perpendicular to said anchor portion and a second portion extending angularly rearwardly.

UNITED STATES PATENT OFFICE
CERTIFICATE OF CORRECTION

Patent No. 3,604,736 Dated September 14, 1971

Inventor(s) Lawrence T. Vance

It is certified that error appears in the above-identified patent and that said Letters Patent are hereby corrected as shown below:

Column 3, line 17, "meal" should read -- metal --. Column 4, line 17, "effecting" should read -- effected --; line 53, "withdraw" should read -- withdrawal --. Column 5, line 62, "fade" should read -- face --.

Signed and sealed this 1st day of August 1972.
